UNITED STATES PATENT OFFICE.

SIDNEY GEORGE BROWN, OF NORTH ACTON, ENGLAND.

ELECTRICAL RELAY.

Application filed August 28, 1922. Serial No. 584,736.

To all whom it may concern:

Be it known that I, SIDNEY GEORGE BROWN, a subject of the King of Great Britain, residing at Victoria Road, North Acton, in the county of Middlesex, England, have invented certain new and useful Improvements in or Relating to Electrical Relays, of which the following is a specification.

This invention relates to electrical relays 10 adapted for use in the amplification of telephone speech currents, of the type in which a microphone is operated by an armature in the form of a vibratory reed bridging the gap between the poles of a receiving polarized electromagnet.

According to this invention the reed operates the vibrating member of a differential microphone in the local or retransmitting circuit of the relay.

20 In a suitable construction embodying this invention a pair of receiving coils of fine wire are wound on laminated cores forming the pole pieces of a horse shoe permanent magnet, the cores being directed towards each other, leaving a gap across which extends the vibrating end or portion of a flat steel reed, the other end of which is firmly secured to a baseplate by two screws. The vibrating reed, at or towards its free end, 25 carries the centre carbon or plate of the differential microphone, preferably upon the end of a pin secured on the reed. The diameter of the centre carbon is preferably about 0.35 inch. The microphone may be 30 of the aperiodic differential type in accordance with the specification of my British Patent No. 120260.

Oscillations of the current set up variations in the magnetic field which cause the 40 reed, together with the centre carbon of the microphone, to vibrate. The microphone is connected to a battery of, say 6 volts, the centre carbon, which is subject to vibration by the reed, being connected to the middle 45 point of the battery while the outer carbons or plates are connected to the positive and negative terminals. Or the outer plates may be connected through the primary windings of two transformers to the same battery 50 terminal, the opposite terminal being connected to the central plate. If a transformer is used the receiving circuit for the relayed current is connected through the transformer secondaries.

55 In order that the said invention may be clearly understood and readily carried into

effect, the same will now be described more fully with reference to the accompanying drawings, in which:

Figure 1 is a side elevation, Figure 2 an 60 end elevation and Figure 3 a plan of relay mechanism embodying this invention.

Figures 4 to 7 show details of the mechanism.

Figure 8 is a diagram of the electrical connections; and

Figures 9, 10 and 11 illustrate a constructional modification of the device.

Figure 12 is a view, similar to Figure 5, showing a compound microphone.

A is the permanent magnet having pole pieces *a* on which the two receiving coils B are mounted. C is the vibrating reed. D is the differential microphone. E is a support or standard carrying the magnet, reed, 75 microphone and other members of the mechanism and itself mounted upon a base F. G is a cover fitted over the device and attached to the base F.

In the construction illustrated in Figures 80 1 to 8 the magnet A is of the ordinary horse shoe shape, but the actual form is immaterial. The pole pieces *a*, which are preferably laminated, are secured by screws *a'* on the corners of the magnet limbs, which 85 are chamfered so that the pole pieces approach one another at about right angles, the adjacent ends being shaped so as to provide a plane surface on each side of the narrow gap across which the reed C extends, the 90 reed being parallel to the longitudinal axis of the magnet.

The form of the reed preferred is shown 95 in Figures 6 and 7, the part *c* being secured by screws to the upright part of the support E, the base plate of which is fixed to the base F. The portion *c'* of the reed, which tapers off from the middle to the sides, bridges the pole gap and the flat face of the reed is arranged to lie as close as is 100 practicable to the parallel face of the pole pieces *a* as indicated in Figure 2, without, however, coming into contact with them.

As the reed is rigidly fixed at its end *c* to the support E the magnet is arranged to 105 be adjusted to bring the pole pieces *a* accurately into position relatively to the reed. For this purpose the magnet is secured by the aid of the clamping plates H, H¹ provided with clamping and securing screws, or 110 bolts. The forward plates H are secured by the screw bolts *h* on which are fitted the

clamping nuts h^1 , the bolts themselves being screwed into the support E. The position of the forward end of the magnet is adjusted by these bolts and nuts while for fine adjustment of the magnet pole pieces relatively to the reed one of the rear clamping plates H^1 , which are clamped on the magnet near its bend by the screws h^2 , receives the end of a set screw h^3 which passes through a hole in the support E and is adjusted from the other side of the support, a strong spring h^4 around the said set screw pressing the end of the magnet away from the support. A slight turn of the screw h^3 allows of very close adjustment of the pole pieces a relatively to the reed. A small collar h^5 on the head of the set screw can be filed away at one side after adjustment and a small screwed stud h^6 provided on the support E to prevent accidental turning.

The microphone D comprises a solid block casing d secured on the support E by the screw d^1 and the pegs d^2 . The microphone is preferably of the aperiodic differential type described in the specification of my British Patent No. 120260 and comprising a central carbon plate d^3 lying in the granule filled cell d^4 without attachment to any part of the microphone and supported entirely between the two granule layers and the side lining d^6 , which may be of pile fabric such as velvet, allowing of free axial movement of the carbon plate without side displacement. The granules are packed on both sides of the centre plate d^3 and between the outer plates d^6 .

The centre plate d^3 of the microphone is rigidly connected through the rod d^7 to the tongue c^2 on the end of the reed C so that any vibration of the reed due to the reception of telephone currents in the coils B is transmitted to the centre plate of the microphone, a movement in one direction causing increased compression in the granules at that side of the plate and a loosening of the granules at the other side so that the resistance is varied in opposite directions at the two sides of the microphone. The diameter of the centre plate d^3 is preferably about 0.35 inch, but the precise dimensions would vary with the general size of the instrument and the work for which it is adapted.

It is necessary for the reed C to be prevented from coming in contact with the poles a of the magnet as the reed might stick to the poles. At the same time the adjustment must be made so that the reed is as close as possible to the poles without actual contact being permitted at any time. To prevent the risk of contact a small adjustable stop is provided in the form of a screw J mounted on the magnet poles. The mounting may conveniently be arranged by fitting the screw stop J in the head j of the clamp screw j^1 which clamps the two small

plates j^2 on the adjacent pole pieces a , the screw j^1 extending between the pole pieces a little behind the front faces as shown in Figures 1 and 2. By adjusting the screw stop J, the end of which lies just behind the tongue c^2 of the reed, the reed is prevented from accidentally meeting the faces of the pole pieces, but is allowed to approach them very closely so as to reduce the air gap to a minimum.

A suitable arrangement of circuit for the microphone relay is shown in Figure 8, which is a diagrammatic plan. The two coils B are connected to the terminals K, to which the receiving circuit is connected, while the centre plate d^3 of the microphone is connected to one battery terminal L and the outer plates d^6 are connected through the primary transformer coils l to the other battery terminal L. This is given as an example of the differential microphone connections, but the invention is not confined to any special method of connecting up the microphone. The local or retransmitting relay circuit is connected to the terminals M to which the secondary coils m are connected as shown in the diagram. The form of microphone shown in Figure 12 is substantially the same as that illustrated in Figure 5, except that the microphone is divided into two cells d^4 , each of which has a central carbon plate d^3 supported between the granule layers in the cells and lying within the side lining d^6 , both the central plates d^3 being rigidly mounted on the rod d^7 . This compound microphone is especially useful in connection with a loud speaking telephone system.

In Figures 9, 10 and 11 a modified construction is shown of smaller size and more compact form, designed more especially for use as an amplifier in aural apparatus for the deaf, but adapted for other purposes where an amplifier of small size is required. The principle of the modified device is identical with that already described, but for convenience the device is circular and comprises a part circular magnet A¹ mounted on the circular supporting base E¹ to which it is secured by the screws a^2 , which also serve to fix the pole pieces a^3 , these pole pieces projecting transversely across the end of the magnet and approaching close to each other at the centre to leave a small air gap bridged by the reed C which is secured at one end by the screw a^4 on the post e of the base E¹. The pole pieces a^3 may be in the form of a single plate with a slot cut at the centre to form an air gap and leaving narrow bridging bars at each side.

To allow for fine adjustment between the reed and the magnet poles the post e is made in a separate piece from the base E¹ but is fixed by riveting in the base and can yield slightly in a resilient manner under the

pressure of the small adjusting screw e^1 secured in the base under the arm e^2 of the post. By adjustment of this screw the angle of the post and the reed can be adjusted 5 sufficiently to give the required fine adjustment of the reed relatively to the magnet poles. The reed is prevented from touching the pole pieces by the screw stop J^1 corresponding to the screw stop J of the previously 10 described construction, the screw stop being carried by the small bracket e^3 on the base E^1 .

The microphone D^1 is of similar type to that already described, but of much smaller 15 and lighter construction and is mounted on the back of the base E^1 which is recessed to receive the casing, the latter being screwed upon the supporting plate d^8 of insulating material, the plate lying in a recess in the 20 base E^1 . The rod d^8 connected to the centre plate of the microphone D^1 is attached to the part c^1 of the reed C^1 and not to the tongue c^2 as in the previous case. The microphone terminals are indicated at L^1 25 responding to the terminals L of the previously described construction.

What I claim and desire to secure by Letters Patent of the United States is:—

1. In an electrical relay, a receiving polarized electromagnet having closely approaching pole pieces, a vibratory armature reed bridging the gap between the poles, a differential microphone in the local or retransmitting circuit, means for connecting the vibratory member of said microphone to the said reed, and means for effecting fine adjustments between the electromagnet and the reed.
2. In an electrical relay, a receiving polarized electromagnet having closely approaching pole pieces, a vibratory armature reed bridging the gap between the poles, a differential microphone in the local or retransmitting circuit, a rod rigidly connecting the vibratory member of the microphone to said reed, and means for effecting fine adjustments between the electromagnet and the reed.
3. In an electrical relay a receiving polarized electromagnet, the poles of which closely approach each other, a stationary support, a differential microphone, the casing of which is fixed on said support, a vibratory armature reed fixed at one end and bridging the gap of the magnet poles and connected rigidly to the vibratory member of the differential microphone, and a fine adjustment means for the said electromagnet by means of which its poles can be adjusted closely to the reed.
4. In an electrical relay a receiving polarized electromagnet, the poles of which closely approach each other, a stationary support, a microphone, the casing of which is fixed on said support, a vibratory armature reed fixed at one end and bridging the gap of the magnet poles and connected rigidly to the vibratory member of the microphone, and a fine adjustment means between the said electromagnet and its support by means of which its poles can be adjusted closely to the reed.
5. In an electrical relay, a permanent magnet of horseshoe type provided with closely approaching pole pieces, receiving coils mounted on the pole pieces, a stationary support for the magnet, a carrying member securing the magnet towards its pole end to the said support, a mounting for the rear end of the magnet provided with a screw adjustment between the support and the magnet by which the position of the magnet poles can be accurately adjusted by slight angular movement of the magnet, a stationary differential microphone, and a vibratory armature reed fixed towards its free end to the vibratory member of the differential microphone and secured to the stationary support at the other end.
6. In an electrical relay, a permanent magnet of horseshoe type provided with closely approaching pole pieces, receiving coils mounted on the pole pieces, a stationary support for the magnet, a carrying member securing the magnet towards its pole end to the said support, a mounting for the rear end of the magnet provided with a screw adjustment between the support and the magnet by which the position of the magnet poles can be accurately adjusted by slight angular movement of the magnet, a stationary microphone, and a vibratory armature reed fixed towards its free end to the vibratory member of the microphone and secured to the stationary support at the other end.
7. In an electrical relay, a receiving polarized electromagnet having closely adjacent pole pieces, a vibratory armature reed bridging the gap between the poles, a compound microphone comprising a plurality of differential microphones and means for rigidly securing the central vibratory members of the said microphones together and to the armature reed.

SIDNEY GEORGE BROWN.
